Attorney.

UNITED STATES PATENT OFFICE.

ALEXANDER MONROE CRAIG, OF WESTPORT, CANADA.

TUG AND TRACE COUPLING.

SPECIFICATION forming part of Letters Patent No. 709,471, dated September 23, 1902.

Application filed March 5, 1902. Serial No. 96,743. (No model.)

To all whom it may concern:

Be it known that I, ALEXANDER MONROE CRAIG, a subject of the King of Great Britain, residing at Westport, in the county of Leeds, 5 in the Province of Ontario, in the Dominion of Canada, have invented certain new and useful Improvements in Tug and Trace Couplings, of which the following is a specification.

My invention relates to improvements in 10 trace-couplings, for which I have obtained Letters Patent of the United States bearing date the 27th day of August, 1901, numbered 681,443, and my present invention has for its object to make a coupling more simple and 15 effective in operation, to avoid puncturing the trace, and thereby weakening it, and to perfect the locking connection to couple and uncouple.

My invention consists in certain features of 20 construction, which will be hereinafter described, and set forth in the claim.

Figure 1 is a plan of my improved tug and trace members coupled; Fig. 2, a longitudinal section of the same; Fig. 3, a section of the 25 tug member on line $x-x$, Fig. 1; Fig. 4, a plan of the trace member inverted, and Fig. 5 a section of Fig. 1 on line $y-y$.

A is the tug member of the coupling, said member being a flat straight metal bar having 30 at one end a loop A' to insert a trace (shown in dotted lines in Fig. 2) and transversely a loop A² to receive the back-strap of a harness, which strap is perforated with a series of holes to engage a stud A³ to support 35 the coupling, as described in my said patent. The other end of the tug member A has integrally a finger A⁴, to which the tug-strap (shown in dotted lines in Fig. 2) is riveted through holes A⁵ therein.

A⁶ is a single slideway or channel extending longitudinally from near the loops A' A² to near the finger A⁴ and is beveled or chamfered on the edges to hold therein slidingly a guide-lug hereinafter referred to.

A⁷ represents a series of elongated perforations in plate A correlative on opposite sides of the slideway at suitable distances apart according to the desired degree of adjustment of the trace.

The trace member B of the coupling has 50 holes B' near one end to secure the trace thereto by rivets, and the other end has an enlarged head B², dished on the under side, and a slot B³ in the upper face. Within the dished head B² is journaled in bearings there-in a rock-shaft B⁴, having two radial tongues B⁵, extending downwardly therefrom to engage the perforations A⁷ in plate A, and upwardly said shaft has a thumb piece or lever B⁶, which passes through the slot B³ and bent 60 to be flush with the external surface of the head B² to prevent accidents or untimely uncoupling.

B⁷ represents a pair of spiral springs wound around the rock-shaft to keep the tongues in 65 the perforations A⁷ and to react the shaft after the tongues have been forcibly lifted out of the perforations, and when so disengaged the trace member is adjustable slidingly on the tug member to lengthen or 70 shorten the adjustment of the trace. To raise the thumb-lever from its flush position to uncouple, the trace is eased up by hand, so that the tongues B⁵ will be pressed against the opposite end of the elongated perforations 75 A⁷. The thumb-lever B⁶ will then rise to a vertical position, so that it may be easily retained by the thumb while adjustment of the trace is being effected.

The under side of the enlarged head B² has 80 intermediately of the tongues a dovetail or flanged lug B⁸, which slides in the channel or slideway A⁶ and frictionally engages its chamfered edges to prevent disconnection while adjusting the trace. The plate A is 85 depressed at the looped end, so that said lug and flanges may enter the termination of the slideway or channel for connection of the trace and tug members.

I claim as my invention—

In a tug and trace coupling, the combination 90 of a tug member having a longitudinal slideway or channel and correlative perforations on opposite sides thereof, and a trace member having an enlarged head dished on the 95 under side and containing a rock-shaft having an elbow thumb-lever projecting through said head and flush therewith, two tongues

engaging said perforations in the tug member, and a guide-plug sliding in said channel or slideway to hold the tug and trace members connectedly, and a spring to keep said 5 tongues in coupling engagement with the tug member, as set forth.

In testimony whereof I have signed my

name to this specification in the presence of two subscribing witnesses.

ALEXANDER MONROE CRAIG.
